UNITED STATES PATENT OFFICE

PAUL E. KLEINEBERG, OF BREWSTER, NEW YORK, ASSIGNOR TO AMERICAN ASSEMBLING MACHINE COMPANY, OF NEW YORK, N. Y., A CORPORATION OF DELAWARE

BOOK-COVERING MACHINE

Application filed October 7, 1926. Serial No. 140,124.

My invention relates to book or pamphlet covering machines and more particularly to an improved tipping mechanism whereby the flexible covers may be pasted or tipped to the end signatures of separate signature groups immediately after the signature-gathering process has been completed without the necessity of separate handling of the gathered signatures or cover sheets.

The objects of my invention are, among other things, to provide a novel and simplified machine of this type by which the cover sheets may be fed in any suitable manner to the end signature groups travelling on a suitable conveyor in upright position so that the operation of making the books may be both automatic and continuous. In the form of my present improvement the books or signature groups may be brought automatically from the signature-gatherer or like machine, such as a stitcher, in a horizontal plane and in upright position in conjunction with an improved tipping mechanism to prevent the application of surplus paste or glue from the paste-roller on the trip-pressure roller arranged oppositely to such paste-roller in the event that no cover sheet has been fed to or conveyed along side of a particular book which is being forwarded by the conveyor.

A further feature of my invention is to provide an improved form of automatic trip mechanism controlled by detectors arranged on either side of the advancing book and located over the paste-pots for moving the trip pressure-roller into and out of operative relation with the paste-applying roller as each book is advanced by the book conveyor so that the paste may be applied only on the inner side of the cover sheets as required for the separate books and not on the coacting pressure roller in the absence of a cover sheet. A further feature of my invention is to provide a novel and improved form of tipping jaws which are designed thereafter to press the cover sheets against the end signatures of the book after such sheets have received the proper amount of paste along their inner lower margins, such jaws being actuated in proper timed relation

with the book conveyor which advances the books through the machine.

By my improvements the successive books or pamphlets travelling in a horizontal direction and in an upright position may have their cover sheets readily applied to the exposed end signatures coupled with automatic means for tripping the tipping or pasting mechanism on either side of the book, which means are controlled by the absence of a cover sheet on one side or the other. Further objects and advantages will be herein-after described and then pointed out in the claims. The drawings show the machine in a preferred form and are illustrative of the invention.

In the drawings, Fig. 1 is a general top plan view of a book-covering machine showing my improvements;

Fig. 2 is a detailed plan view of the trip mechanism;

Fig. 2a is a detail view of part of Fig. 2 showing the trip pressure-roller latched and held away from the paste-roller which is in their normal position;

Fig. 3 is a side elevation of Fig. 2;

Fig. 4 is an end view looking from the right in Figs. 2 and 3;

Fig. 5 is a side elevation of the drive for the tipping jaws taken on the line 5-5 of Fig. 1;

Fig. 6 is a plan view of the tipping jaws and drive therefor;

Fig. 7 is a sectional elevation of the paste-pot and superposed book conveyor and paste-wheels taken on the line 7-7 of Fig. 8; and

Fig. 8 is a plan view of the paste wheels and drive therefor.

Similar numerals refer to similar parts throughout the several figures.

Referring to the drawings, the book conveyor 9 having spaced-apart horizontally-disposed fingers 10 extending over the horizontal race-way 11 is driven by the sprocket 12 fastened to the stub-shaft 13 journaled in the bearing 14 and having the bevel gear 15 meshing with the bevel gear 16 fastened to the line shaft 17 driven by the sprocket 18 from any suitable source of power (not shown). Secured to the race-way 11 are the

two oppositely disposed vertical guide-plates 19 between which the separate books 20 are advanced along the race-way 11 by the fingers 10 in the direction of the arrow shown in Fig. 1.

5 The cover sheets 21 which are fed to either side of the books 20 are then conveyed between the guide-plates 19 by the conveyor fingers 10. In Fig. 1 a cover feeder 22 is 10 shown in dot-and-dash outline comprising two sets of feed-wheels 23 (four on each side) by which the cover sheets 21 are separated from suitable piles and brought into parallelism with the end signatures of the books 20 15 in spaced relationship with the guide-plates 19 to be advanced with the books 20 as shown in Figs. 4 and 7.

Located beneath the book conveyor and race-way 11 are the right and left paste-pots 24 and 25 with their respective paste-applying devices which are alike in construction and are shown in detail in Figs. 7 and 8. A description of one set will suffice for both. Each paste pot has a subjacent hot-water reservoir 26 provided with the funnel 27 and pet-cock 28. The vertically disposed paste-wheel 29 is mounted on the spindle 30 and the periphery of the wheel 29 is spaced slightly from the bottom of the paste pot (Fig. 7). The spindle 30 is journalled in the adjustable sleeve 31 threaded in the bracket 32 and is held in position by the check-nut 33 which bears against the outer end of the bracket 32. The outer end of the sleeve 31 presses firmly 35 against the hub of the drive gear 34 which is rigidly held on the spindle 30 by the clamp nut 35 and lock nut 36. Fastened to the drive-gear 34 are the paste wheel sprockets 37 driven by the chains 38 passing over the sprockets 39 keyed to the drive shaft 40 (Fig. 1) journalled in the bearing 41. The drive shaft 40 carries the bevel gear 42 meshing with the bevel gear 43 fast on the line shaft 17. The idler sprocket 44 is rotatably mounted on the stud 45 which is fastened to the idler lever 46 adjustably secured to the carrier shaft 47 fastened to the side of the water reservoir 26 (Figs. 7 and 8) by which any slack in the chain 38 is taken up. Running in contact with the peripheral margin of the paste wheel 29 is the horizontally-disposed paste-roller 48 mounted on the stub-shaft 49 to which is fastened the spiral pinion 50 meshing with the spiral gear 51 mounted on the stub-shaft 52 journalled on the cap-bracket 53 to which shaft 52 the drive pinion 54 is keyed and engages the drive gear 34 (Figs. 7 and 8). The paste wheel 29 and the paste-roller 48 are thereby 55 driven in unison at the same peripheral speed; by laterally shifting the sleeve 31 the paste wheel 29 may be moved horizontally in either direction whereby the thickness of the paste film or amount of paste to be applied to 60 the cover sheets 21 by the paste-roller 48 may

be regulated to meet the requirements of the job. As shown in Fig. 8 the scraper plate 55 having the slot 56 cut therein through which the paste-wheel 29 revolves causes any excess paste on the outer side of the wheel 29 to be returned to the paste pots. The paste-roller 48 normally applies paste to the inside of the cover sheets 21 (Fig. 7), the lower margin of which pass between the horizontally-aligned paste-rollers 48 and the trip pressure rollers 57 by which such lower margins of the sheets 21 are held against the paste-rollers 48 to have the required amount of paste applied to the inside of the sheets 21 as shown in Fig. 7.

70 The mechanism for moving the trip pressure-rollers 57 into and out of contact with the cover sheets 21 and the paste-rollers 48 as each book is advanced by the conveyor 9 automatically controlled by a detector on either side of the book so that rollers 57 may be held away from the paste-rollers 48 should a cover sheet 21 fail to be fed and conveyed along the guide-plates 19 in mutual parallelism with a book 20 travelling along the conveyor 9 may be widely varied in construction and operation and is best shown in Figs. 1-4 and 7: The U-shaped guide channel 58 is horizontally disposed above one side the race-way 11 (Fig. 4) and is supported on the standards 59 so that the ends of conveyor fingers 10 rest in and pass along such channel 58 as shown in Figs. 2 and 4. Journalled in the bearings 60 secured to the channel 58 is the rock shaft 61 to the forward end of which is fastened the cam-bracket 62 carrying the detector-hook release cam 63 adapted to be engaged and lifted by each conveyor finger 10 to rock the shaft 61 successively. The opposite end of the rock-shaft 61 carries the cam-bracket 64 with the trip-cam 65 secured on its side (Figs. 2 and 3) which cam 65 is also adapted to be engaged and lifted by each conveyor finger 10 in the forward movement of the conveyor 9. On the opposite side of the race-way 11 suitable bearing brackets 66 (Fig. 2) are fastened to the under edge of the race-way 11 (Fig. 4) in which brackets the rock-shaft 67 is journalled. The connecting rod lever 68 is fastened to the rock-shaft 67 and the end of the lever 68 is pivoted to the connecting rod 69 pinned to the end of the lever 70 secured to the rock-shaft 61. The coil-spring 71 fastened to the collar 72 adjustably secured to the rod 69 by the set-screw 73 and to the pin 74 secured to the race-way 11 (Figs. 2 and 3), normally pulls the rod 69 to the left in Fig. 4 and resists the action of the cams 63 and 65 in rocking the shaft 61 counter-clockwise (Fig. 4).

roller 57 and operating mechanism will suffice for both: Referring to Figs. 2-4, the roller 57 is journaled in the sleeve 75 mounted on the end of the rock-lever 76 adjustably secured to the vertical sleeve 77 journaled on the stub-shaft 78 passing through the race-way 11 and rigidly secured thereto by the nut 79. Also adjustably secured to the sleeve 77 is the rock-lever 80 having pinned thereto the link 81. The trip-operating levers 82 and 83 are each pinned to their respective links 81 and each lever 82 and 83 carries the same form of detector hook-catch 84 on its free end. Looking at Figs. 3 and 4 the operating lever 82 is fastened to the upper rock-shaft 61 while the operating lever 83 is secured to the lower rock-shaft 67 on the opposite side of the race-way 11. The rock-arm 85 is adjustably secured to the rock-shaft 61 and the light coil-spring 86 connecting the arm 85 to the lever 82 normally draws the arm 85 downwardly against the stop 87 on the lever 82. In like manner the rock-arm 88 is adjustably secured to the rock-shaft 67 with the spring 89 connecting the arm 88 to the lever 83 normally draws the arm 88 upwardly against the stop 91 on the lever 83 by which these arms 85 and 88 are held in yielding connection with the respective stops 87 and 91.

The detectors 92 and 93 on either side of the race-way 11 are pivoted on pins 94 and 95 respectively secured in brackets 96 and 97 respectively mounted on upright standards 98 and 99 respectively affixed to the either side of the race-way 11 (Fig. 4). Fastened to and rocking with the detectors 92 and 93 are the detector hooks 100 and 101 respectively backed by the light springs 102 and 103 fastened to the brackets 96 and 97 which springs 102 and 103 respectively force the tips of the detectors 92 and 93 against the cover sheets 21 as they pass sidewise along the inclined plates 104 and 105 fastened to the guide plates 19, such plates being formed U-shaped in cross-section as shown in Fig. 4. The detector hooks 100 and 101 are adapted to coact with the catches 84 secured to the operating levers 82 and 83 respectively. Fig. 2 shows the normal coacting engagement of catch 84 and hook 100 with the detector 92 resting within the plate 104 in the absence of a cover sheet 21 and the trip pressure-roller 57 held away from the paste roller 48. Figs. 2 and 4 show the detector hooks 100 and 101 released from the catches 84 due to the cover sheets 21 holding the detector tips out of the grooves in the inclined plates 104 and 105 so as to bring the trip pressure-rollers 57 against the paste rollers 48 to apply paste to the inside lower margins of the sheets as the books 20 pass along the raised runway 106 extending along the race-way 11 between the guide-plates 19 as shown in Fig. 7. These devices are suitably timed with the forward movement of the cover sheets and books on the conveyor 9.

After the successive books 20 with the cover sheets 21 tipped to the end signatures have been advanced along the conveyor 9 beyond the oppositely-disposed tipping mechanisms just described (to the left in Fig. 1), the books 20 pass between the oppositely-disposed tipping jaws which firmly press the cover sheets against the books proper, the operation of these jaws being adjusted to the proper timed relation with the book-conveyor 9.

Such tipping jaws and their operating mechanism are best shown in Figs. 1, 5 and 6. Secured to the underside of the race-way 11 is the transverse bracket 107 which supports the depending bearings 108 and 109 in which the horizontal shafts 110 and 111 are journaled. The shafts 110 and 111 carry the sprockets 112 and 113 respectively over which passes the sprocket chain 114. The idler sprocket 115 journaled on the pin 116 adjustably mounted on the vertical stub-shaft 117 secured to the bracket 107 bears on the under side of the chain 114 to take up any slack in such chain 114 (Fig. 5). The shaft 111 has affixed thereto the drive sprocket 118 actuated by the chain 119 passing over the sprocket 120 secured to the line-shaft 17 (Figs. 1 and 5). The idler sprocket 121 journaled on the pin 122 adjustably mounted on the upright bar 123 bears on the under side of the chain 119 to take up any slack in such chain 119 (Figs. 5 and 6). The shaft 110 carries at either end two spiral gears 124 and 125 which engage with spiral pinions 126 and 127 affixed to upright shafts 128 and 129 respectively journaled in the sleeves 130 and 131 secured to the transverse bracket 107. Mounted on the tops of the shafts 128 and 129 are the rotatable disks 132 and 133 which revolve in the direction of the arrows in Figs. 1 and 6. Arranged above the disks 132 and 133 is the tipping jaw 134 having its flat face 135 disposed above the race-way 11 as shown in Fig. 5. This jaw 134 has two transverse slots 136 and 137 cut therein through which pass the studs 138 and 139 respectively which are fastened to the bracket 107 to hold the jaw 134 in proper aligned position yet allowing a transverse horizontal movement with respect to the race-way 11. In like manner the shaft 111 carries two spiral gears 140 and 141 which engage with spiral pinions 142 and 143 affixed to the upright shafts 144 and 145 respectively journaled in the sleeves 146 and 147 secured to the transverse bracket 107. Mounted on the tops of the shafts 144 and 145 are the rotatable disks 148 and 149 which revolve in the direction of the arrows (Figs. 1 and 6). Arranged above the disks 148 and 149 is the other tipping jaw 150 oppositely disposed to the jaw 134 with its flat face 151 in mutual parallelism with the face 135 of the jaw 134 (Figs. 1 and 6). This jaw has two

transverse slots 152 and 153 cut therein through which pass the studs 154 and 155 respectively fastened to the bracket 107 to hold the jaw 150 in position yet allowing a transverse horizontal movement with respect to the jaw 134 to allow for different thicknesses in the books 20 travelling on the race-way 11. The disks 132 and 133 have pinned thereto the cam-rollers 156 and 157 respectively which engage the cam surfaces 158 and 159 of the tipping jaw 134; in like manner the disks 148 and 149 have pinned thereto the cam-rollers 160 and 161 respectively which engage the cam surfaces 162 and 163 of the tipping jaw 150. The jaws 134 and 150 have a rotary movement in conjunction with their mutual reciprocations as the four disks 132, 133 and 148, 149 are rotated, since the pins holding the cam-rollers 156, 157 and 160, 161 respectively are connected by straps (Fig. 6) which cause the jaws 134 and 150 to describe an orbital path relatively to each other as they are reciprocated. When the disks 132, 133 and 148, 149 are rotated in unison by the mechanism just described, the two tipping jaws 134 and 150 are reciprocated in unison to press the cover sheets 21 of the book 20 passing along the race-way 11 between these jaws with a gradually increasing pressure after which the jaws 134 and 150 release the book when the revolutions of these four disks withdraw the two jaws so that they no longer press against their respective cover sheets 21 of the book previously in contact with the jaws 134 and 150 as has just been described.

After the books 20 have travelled along the race-way 11 beyond the tipping jaws 134 and 150, they are advanced between the converging conveyor chains 164 and 165 which pass around the sprockets 166 and 167 respectively driven in the direction of the arrows shown in dot and dash outline in Fig. 1. Such books are carried by these chains 164 and 165 in upright position out of the machine.

In operation the successive books 20 enter the race-way 11 from the right in Fig. 1 and the cover sheets 21 are separated and brought in alinement with the end signatures of the books between the guide plates 19 by the cover sheet-feeder 22 and between the spaced-apart conveyor fingers 10 on the conveyor 9. As the conveyor 9 advances in the direction of the arrow both books 20 and cover sheets 21 are forwarded and the paste-roller 48 and trip pressure-roller 57 on each side of the machine are held separated as shown in Fig. 2^a. However the end of the conveyor-finger 10 in its forward movement engages the detector-hook release cam 63 which rocks the shaft 61 in a counter-clockwise direction (Fig. 4) thereby disengaging the catches 84 of the trip-operating levers 82 and 83 from the detector hooks 100

and 101, the various parts assuming the several positions shown in Fig. 2 with the cover sheets 21 pressed between the rollers 48 and 57 and the detectors 92 and 93 held out of their respective groove plates 104 and 105 by the cover sheets; the conveyor finger 10 is shown as just releasing the cam 63. In such positions the two paste-rollers 48 apply the film of paste on their peripheries to the inner lower margins of the two cover sheets 21 (Fig. 7) which are held against the rollers 48 by the pressure-rollers 57. However should a misfeed of a cover sheet 21 occur on either side of the book 20, the tip of the detectors 92 or 93 would be forced into the grooved plate 104 or 105 respectively by the springs 102 or 103 in the absence of a sheet, which would bring the parts into the positions shown in Fig. 2^a with the particular pressure-roller 57 held out of contact of its coacting paste-roller 48 and no paste would be transferred from the roller 48 onto the periphery of the pressure-roller 57. When the conveyor fingers 10 in their forward travel engage the trip cam 65, the shaft 61 is rocked so as to allow the coil spring 71 to restore the connecting mechanism shown more particularly in Figs. 2, 3 and 4 into its normal position, the trip-operating levers 82 and 83, by the yielding connection afforded by the springs 86 and 89, being brought into their coacting engagement with the detector hooks 100 and 101 until the next conveyor finger 10 raises the hook-release cam 63 in the next cycle of operation as the successive books 20 and their alined cover sheets 21 are advanced along the race-way 11.

Thereafter the books 20 and the thereto pasted cover sheets 21 are forwarded between the coacting horizontally-movable tipping jaws 134 and 150 which in turn force the cover sheets 21 in firm contact with the book 20 with a gradually increasing pressure that is thereafter relaxed as the rotating disks 132, 133 and 148, 149 continue their revolutions as has been hereinbefore described. The books with their cover sheets tipped to the end signatures of the book are then brought between the conveyor chains 164 and 165 which carry the books in upright position out of the machine.

I claim as my invention:—

1. In a book-covering machine having in combination a pasting roller having its periphery vertically disposed, a coacting pressure roller, means for feeding separated cover sheets in vertical alinement between the two rollers, and means for separating and holding the pressure roller out of coactive engagement with the pasting roller to render the latter inoperative in the absence of a cover sheet therebetween.

2. In a book-covering machine having in combination a pasting roller having its periphery vertically disposed, a coacting pres-

- sure roller normally held in engagement by the sheets with the pasting roller, means for feeding separated cover sheets in vertical alinement between the two rollers, and
- 5 means for separating and holding the pressure roller out of coactive engagement with the pasting roller to render the latter inoperative in the absence of a cover sheet therebetween.
- 10 3. In a book-covering machine having in combination a pasting roller having its periphery vertically disposed, a coacting pressure roller, means for feeding separated cover sheets in vertical alinement between the two
- 15 rollers, and means for positively separating and holding the pressure roller out of coactive engagement with the pasting roller to render the latter inoperative in the absence of a cover sheet therebetween.
- 20 4. In a book-covering machine having in combination, a rotary pasting roller having its periphery vertically disposed, an idler coacting pressure roller, means for feeding separated cover sheets in vertical alinement
- 25 between the two rollers, means controlled and actuated by the passing sheets for bringing said rollers into engagement, and a trip mechanism controlled and actuated by the absence of a cover sheet for throwing the
- 30 pressure roller out of contact with the pasting roller.
5. In a book-covering machine having in combination, a rotary pasting roller having its periphery vertically disposed, an idler
- 35 coacting pressure roller, means for feeding separated cover sheets in vertical alinement between the two rollers, means controlled and actuated by the passing sheets for bringing said rollers into engagement, and a trip
- 40 mechanism controlled and actuated by the absence of a cover sheet for positively throwing and holding the pressure roller out of contact with the pasting roller.

PAUL E. KLEINEBERG.
